UNITED STATES PATENT OFFICE.

JOHN KILBURN, JOHN WESLEY FAIRLEY, THOMAS BESELL KIDNER, WILLIAM HERBERT IRVINE, AND WILLIAM TURNBULL CHESTNUT, OF FREDERICTON, NEW BRUNSWICK, CANADA, ASSIGNEES TO MONITOR GAS GENERATOR COMPANY, OF NEW YORK, N. Y., A CORPORATION OF NEW YORK.

ACETYLENE-GAS GENERATOR.

1,029,873.

Specification of Letters Patent. Patented June 18, 1912.

Application filed July 6, 1911. Serial No. 637,097.

To all whom it may concern:

Be it known that we, JOHN KILBURN, JOHN WESLEY FAIRLEY, THOMAS BESELL KIDNER, WILLIAM HERBERT IRVINE, and 5 WILLIAM TURNBULL CHESTNUT, all subjects of the King of Great Britain, and residing at the city of Fredericton, in the Province of New Brunswick, Canada, have invented certain new and useful Improvements in Acetylene-Gas Generators; and we do hereby declare that the following is a full, clear, and exact description of the invention, such as will enable others skilled in the art to which it appertains to make and use the same.

15 The invention to be hereinafter described relates to gas generators and particularly to acetylene gas generators of the inverted bell variety.

This application is an improvement on the 20 subject matter of application Serial Number 607,708. We do not claim in this application the subject matter of any claim in the application above mentioned nor in our application #637,098, filed July 6th, 1911.

25 In order to more clearly disclose the construction, operation, and use of the invention, reference should be had to the accompanying drawings forming part of the present application.

30 Throughout the several figures of the drawings like reference characters designate the same parts.

In the drawings: Figure 1 is a side elevation of the generator, complete; Fig. 2 is a 35 left hand end view of Fig. 1; Fig. 3 is a vertical longitudinal section of the complete generator; Fig. 4 is an enlarged side elevation of the carbid chamber and attachments, as shown in Fig. 1; Fig. 5 is a view 40 similar to Fig. 4, looking toward the left of Fig. 1; Fig. 6 is a top plan view of Fig. 4; Fig. 7 is a plan view of the drain cock, removed; and Fig. 8 is a front view of the closure retaining device.

45 Referring to the drawings in detail, 1 indicates a gas generating tank provided with an upwardly extending neck 2 adapted to loosely receive a removable cast iron collar having an annular perforated supporting 50 flange 3. Upon flange 3 rests a similar and coöperating flange of a corresponding collar similarly fitted about and supporting the lower end of a removable carbid receptacle

4 of usual and well known form. The two annular flanges may be readily and solidly 55 connected by bolts or the like, as will be evident. If desired, the collars may be soldered or otherwise solidly secured to the neck 2 and the carbid receptacle 4. The upper part of this generating tank is connected by an elbow pipe 5 with a vertical gas delivery pipe 6 which is adapted to deliver the gas to the interior of a bell 7 slidably mounted in the gas tank 8. Gas may be drawn from the gas tank through the 60 pipe 9, in the usual manner. Centrally arranged within the chamber 8 is a hollow guide tube or pipe 10 adapted to fit loosely within a similar tube 11 extending downwardly from the top of the bell. The tube 70 11 is provided with a plurality of perforations 12 arranged at a predetermined point below the top of the bell. When the gas beneath the bell forces it upward to such a point that the perforations 12 are above the 75 surface of the water, the excess gas will escape through the perforations and out through the tube 10 to the lower compartment of the tank 8 and thence through an opening 42 by a pipe to the flue 41, and 80 thence by a suitable vent pipe to the outside of the building in which the generator is placed. In this way, the gas bell cannot be raised, by the gas, beyond a predetermined point.

85 In order to cut off the generation of gas at the proper time, it is necessary to stop the feed of carbid to the generating tank. For this purpose, an operating lever 13 (Figs. 1 and 3) has been provided. The long end of 90 this lever is adjustably connected to an easily fusible strap 55 on the top of bell 7 by means of a threaded rod 56 and coöperating nut 57, which may be a winged thumb nut as shown in Fig. 1 or a slightly modified 95 form as shown in Fig. 3. This lever is fulcrumed on the top of a cup shaped cap 14 provided with an annular, perforated, supporting flange 15, adapted to rest upon and coöperate with a similar flange 16 100 formed on and extending from a flanged ring 17 which is removably seated in a circular opening in the top of the carbid receptacle 4. The flanged ring is adapted to support a cylindrical flanged guard tube 18 105 extending downwardly within the receptacle

to within a short distance of the bottom, as clearly shown in Fig. 3. The cap 14 and annular flange 16 are detachably and securely connected by bolts or the like passed 5 through the perforations of their flanges. The short end of lever 13 is bifurcated and longitudinally slotted. One arm 19 of the bifurcated end of the lever is pivoted to the lever at 20, to swing laterally therefrom. A 10 threaded rod 21 projects through the slot of the lever 13 and is provided with an adjusting nut 22 screwed down thereon. Normally, the arm 19 is held in operative position by means of a rockable yoke 23 pro- 15 vided with off set arms 24 and 25 and pivotally mounted on the end of the stationary arm of the lever 13. The yoke is provided with a notch or recess adapted to receive or seat the end of the movable arm 19 and hold 20 it parallel with the fixed arm of the lever, thereby supporting the nut 22. The off set arm 24 underlies a horizontal rock shaft 26 revolvably journaled in a suitable bearing formed as a part of one side of the cap 14. 25 This shaft is provided with an outer arm 27 detachably connected thereto, and an inner arm 28 which projects downwardly within the guard tube 18. The outer arm is pivotally connected to the lower end of the rod 21 and the inner arm is pivotally connected to the upper end of a valve rod 29 on the lower end of which is fixed a plug valve 30, preferably rubber faced, adapted to close 30 the discharge or delivery opening for de- 35 livering carbid to the interior of the generating tank. Slidably mounted on the valve rod 29, above the plug valve 30, is a cup shaped valve 31 adapted to seat itself, by gravity, slightly in advance of the plug 40 valve 30 and to remain seated a short while after the plug valve has been lifted. The result of this construction is, that as soon as the bell 7 falls below a predetermined point, the short bifurcated end of the lever 13 will 45 be raised, carrying with it the rod 21 and thus raising the valves 30 and 31 to permit carbid to drop from the receptacle 4 to the generating tank 1. The bell then rises as a 50 result of the gas just generated. In this way, the quantity or supply of gas generated is kept fairly constant. Should an excess quantity be suddenly generated, the bell will rise until the excess may escape through the 55 perforations 12 and pipe 10 into the lower compartment of the gas tank. Should this supply of carbid in the receptacle 4 become exhausted and all the gas in the bell 7 be used, it is advisable, of course, to close the delivery opening of the carbid receptacle 60 by seating the valves. This is effected automatically by engagement of the offset arm 24 with the rock shaft 26, as the short end of lever 13 rises, due to the drop of the bell 7. As soon as the off set arm 24 engages the 65 rock shaft 26, the yoke 23 will be rocked on

its pivot and the arm 19 will be freed, moving easily out to inoperative position, thus breaking connection between rod 21 and lever 13 and allowing the lever end to rise while the rod drops. Valves 30 and 31, of course, seat themselves by gravity, as soon as the connection is thus broken. Consequently, under such circumstances, the valves will be closed and remain closed until recharging. In this way, no moisture can 70 pass from the generating tank to the interior of the carbid receptacle, even though the apparatus remain unused for a very considerable period. 75

In order to insure, with absolute certainty, 80 the seating of the valves before recharging of the carbid receptacle, the closure plug 32 is held in place by a threaded rod 33 provided with a wide head or hand wheel 34 and threaded through a yoke 35 mounted 85 to swing above the plug 32—see Fig. 8. Above this head extends the arm 36 of a rod 37 mounted to slide vertically in the bearing or guide 38 fixed to the receptacle 4. Downwardly curved fingers 39 extend laterally from the arm 36 and lie directly over the head 34 and beneath the off set arm 25—between the off set arm 25 and head 34. Consequently, whenever the head 34 rises, as the rod 33 is screwed upwardly to release 90 the plug 32, said head will engage the fingers 39 and arm 36 and carry them upwardly into engagement with the off set arm 25, thus rocking the yoke 23 and freeing the arm 19, to permit the valves 30 and 31 to 95 seat themselves and so cut off the feed of carbid during recharging of the receptacle. 100

In order to avoid excessive pressure in the upper part of the generating tank 1, a safety tube 40 has been provided. This tube extends downwardly through the top of tank 1 and its lower end projects below the normal water line in the tank. The upper end of the tube communicates with an escape flue 41, and thence by a suitable vent pipe 105 before mentioned to the outside of the building in which the generator is placed. Consequently, when the gas pressure in the generator tank exceeds a predetermined point, water will be forced upwardly through a 110 tubular hollow agitator rod 43 and its casting 44 to a sufficient extent to uncover the lower end of tube 40 and thereby permit escape of the excess gas, without causing siphoning of the water in the gas tank, as 115 heretofore. 120

It is essential, of course, to provide means for the escape of the air and gas mixture from the generating tank during recharging, and during the emptying of the generating tank—this operation is more commonly known as venting the generating tank. For this purpose, a by-pass 45 is provided. One end of this by-pass communicates with the upper end of the escape flue 130

41 while the opposite end projects downwardly through the top of the generator tank. At a point just above its passage through the top of the generator tank, the 5 by-pass communicates with the elbow pipe 5. At a point just above this connection, the by-pass is provided with a turn plug or valve 46 adapted to control passage of fluid therethrough. When the turn plug or valve 10 46 is open, the fluid will pass through the by-pass and escape into the flue 41 and thence to the outer air. When closed, the gas generated in the generating tank will pass, by way of elbow pipe 5, into the gas tank. To effect opening of this plug or valve, during charging of the carbid receptacle, the plug is provided with an operating handle 47 which is flexibly connected, by link or like device 48, to the lower end 15 of the sliding rod 37. The result is, that whenever the rod 37 is raised for recharging, the valve 46 will be opened and the chamber 1 will be vented. On the other hand, the rotary drain plug 49 is provided 20 with a handle 50 which is connected by a rod 51 with the handle 47. The connection between the rod 51 and handle 47 is pivotal. Thus, either raising of rod 37 to recharge the carbide holder, or opening of the drain 25 plug, will effect opening of the by-pass valve or turn plug 46, and automatic venting of the generating chamber.

In the preferred form of the invention, the rod is provided with an upper section 35 102 of squared or similar cross section, and adapted to slide vertically through correspondingly shaped openings in the guide brackets secured to the side of the carbide chamber. This arrangement prevents turning 40 of the rod 37 as long as the squared section is in the guide openings of the brackets. The lower portion of the rod, however, is cylindrical. Consequently, when the rod is raised so that this rounded portion is in the 45 opening of the brackets, it is possible to rotate the rod about its longitudinal axis. The link 48, however, can not be swung with the rod 37. Consequently, a swivel connection is provided. This comprises a small 50 stirrup 100 swiveled to the lower end of rod 37, and a pivot bolt 101 or the like passed through the sides of the stirrup and through the upper end of the rod 48. Thus, the arm 55 36 with its fingers 39 may be readily swung out of the way while recharging. At the same time, of course, the drain plug 49 will, necessarily, be opened. Furthermore, the lower end of the squared section of the rod 37 will rest on the upper face of the top 60 bracket and maintain the drain plug 49 in open position, until the rod is again turned back and lowered.

In order to prevent the arm 36 passing above the off set arm 25 instead of beneath it, when the arm 36 is returned to operative

position, a guard finger 103 has been formed on the end of the off set arm 25. This finger is arranged to intercept the arm 36 when rotated in a plane above the off set arm 25.

One particular advantage of having the agitator 43 made as a hollow tube is that it may be used for filling the tank 1 with water.

In order to determine when the water in the tank has reached its proper level, a gage cock 54 is provided. This gage cock is extended through the wall of tank 1 and the wall of the agitator casing and communicates with the interior of the casing.

If desired, an outlet or escape may be provided whereby accumulated air, gas, or mixture of the same, may pass out from the lower compartment of the gas tank 8.

One particular advantage of the cap 14 and its connected parts is the ease and quickness with which it may be removed for inspection.

Another important feature is the placing of all operating parts on the exterior of the apparatus where they are easily accessible and where they may be quickly renewed or repaired, when desired.

It is thought that the operation and use of the invention will be clear from the preceding detailed description.

Changes may be made in the construction, arrangement, and disposition of the several parts of the invention without in any way departing from the field and scope of the same and it is meant to include all such within this application wherein only a preferred form has been disclosed.

Having thus fully described our invention, what we claim as new and desire to secure by Letters Patent is:

1. In combination with a gas generating tank having a vent valve and a drain valve, devices connecting said valves to make them operate together, a sliding rod connected to said devices and having fingers at its upper end, and a screw overlapped by said fingers and adapted to engage them and raise said rod at will opening said valves simultaneously as set forth.

2. In combination with a gas generating tank having a vent and vent valve, a carbide receptacle supplying said tank, a vertically adjustable screw for opening said receptacle to charge the same, a sliding rod having a part overlapping said screw so as to be lifted thereby and connections between said valve and said rod in order that the act of opening said receptacle for charging it may simultaneously vent said tank.

3. In combination with a gas generating tank having a vent, vent valve and drain valve, a carbide receptacle supplying said tank, a vertically adjustable screw for opening said receptacle to charge the same, a

sliding rod having a part overlapping said means so as to be lifted thereby and connections between said valves and said rod in order that the act of opening said receptacle may simultaneously vent and drain said tank.

4. In combination with a gas generating tank having a vent tube, an escape pipe communicating with said tube near the outer end of the latter and having its lower end submerged within said tank, a gas delivery pipe from said tank communicating with said vent tube near the inner end of the latter, a valve arranged in said vent tube between said escape pipe and said gas delivery pipe, a carbide receptacle, a movable device mounted thereon and means connected to said valve and arranged to be acted on by said device for opening the same.

5. In combination with a gas generating tank having a vent tube, an escape pipe communicating with said tube near the outer end of the latter and having its lower end submerged within said tank, a gas delivery pipe from said tank communicating with said vent tube near the inner end of the latter, a valve arranged in said vent tube between the points of junction of these two pipes, means for normally keeping said valve closed, a drain valve for said tank, means connecting the vent valve and drain valve and means for actuating both of said valves simultaneously for the purpose set forth.

6. A carbide receptacle having a charging opening and an outlet opening, in combination with a gas generating tank supplied thereby, a gas tank, a gas pipe connecting the two tanks, an escape flue, a by-pass connecting said pipe to said flue, a valve in said by-pass directing the gas alternately to said gas tank or said flue, movable means attached to said valve, fingers moving with said means, a closure for said charging opening and a screw normally bearing on said closure and arranged to engage and lift said fingers when freeing said closure, in order that said valve may thereby be operated to vent the said generating tank.

7. In combination with a carbide receptacle and a removable closure for its charging opening, a screw for holding said closure in place or freeing it at will, a generating tank having a vent, vent valve, drain and drain valve, a sliding rod provided with connections to these valves for operating them simultaneously and with fingers extending over said screw in order that said rod may be lifted thereby, a valve cutting off the flow of carbide from said receptacle to said tank, means for normally suspending this valve and means extending over said screw and actuated by its upward movement to free the last mentioned valve and allow

it to seat itself simultaneously with the freeing of said closure and the opening of said vent pipe and drain pipe.

8. In combination with a carbide receptacle and an acetylene gas generating tank supplied thereby, a vent for said tank, a valve closing said vent, an arm connected to said valve, a sliding rod, a link pivotally connected at its ends to said arm and said rod, a charging closure for said carbide receptacle and vertically movable means for holding and freeing said closure at will, the said rod being provided with a part overlapping said means and arranged to be lifted thereby for opening said vent valve while opening said closure, said rod being held against turning except when in its highest position for the purpose set forth.

9. A carbide receptacle, an acetylene gas generating tank supplied thereby, a movable yoke, a cut off valve and intermediate devices governed by said yoke, a vent valve for said tank, a rotatable and longitudinally slideable rod arranged to operate said yoke and said vent valve simultaneously, means for sliding said rod longitudinally and means for preventing said rod from turning during its sliding motion.

10. A carbide receptacle, a closure for its charging opening, a generating tank supplied by said receptacle, a vent valve for said tank, a sliding rod having a loose pivotal connection to said valve and means for opening said closure arranged to engage and lift said rod, the said rod being cylindrical in its lower part and provided with a fixed guide which engages its prismatic part to prevent its turning until said rod is lifted high enough for its cylindrical part to enter said guide.

11. A carbide receptacle, a generating tank supplied thereby, a valve governing such supply, devices suspending said valve, a movable yoke for holding said devices in engaging and suspending position, a rod having its lower part cylindrical and its upper part prismatic and arranged to move said yoke for freeing said valve and permitting the latter to close automatically when said rod moves upward, a vent valve for said tank, pivotal connections of said rod to said valve in order that said valve and yoke may be operated together and a guide engaging the prismatic part of said rod to prevent it from turning while it slides upward, said guide and pivotal connections permitting the said rod to turn when the cylindrical part thereof moves up into the guide.

12. A carbide receptacle and its charging closure, in combination with a generating tank supplied thereby, a vent valve for the latter, a closure for the former, a screw for operating said closure arranged to rise as it frees the same, a rod having a part bent

normally over said screw to be engaged for lifting said rod, a prismatic part below said bent part and a still lower cylindrical part, connections between the lower end of said rod and said valve permitting said rod to turn, and a guide adapted to engage the prismatic part of said rod and prevent the latter from turning until it rises sufficiently to bring the cylindrical part into the guide, 10 permitting the rod to be turned for moving its bent part out of position to be engaged by said screw.

13. Interference mechanism for gas generators comprising a pivotally mounted yoke, and a carbide cut-off valve a movable rod adapted to move said yoke, means arranged to be in contact with said rod when it is thus moved and adapted to act on said yoke for freeing the same and allowing the 20 descent of said valve, a vent valve operated by said rod and means for actuating said rod and connections between said rod and vent valve comprising a link, a valve handle, a stirrup loose on said rod and a pivot bolt 25 in said stirrup substantially as set forth.

14. Interference mechanism for gas generators provided with means for controlling the supply of carbide to the gas generating

tank, in combination with said tank, a vent valve for the latter, a sliding rod for actuating said valve and connections between said rod and said vent valve which permit the said rod to turn on its axis beside having endwise movement as set forth. 30

15. In combination with a carbide receptacle having a charging opening and movable closure therefor, means for normally holding said closure on said opening but movable to release the same, a rod arranged to be engaged by said means and moved end- 35 wise in the act of freeing said closure, a generating tank supplied by said receptacle, a vent valve for said tank and swiveling connections between said rod and said valve which permit said rod to turn on its axis. 40 45

In witness whereof we have hereunto set our hands in the presence of two witnesses.
